A. HOLMSTRÖM.
SPRAYER PADDLE WHEEL.
APPLICATION FILED MAR. 10, 1920.

1,391,057.

Patented Sept. 20, 1921.

UNITED STATES PATENT OFFICE.

AXEL HOLMSTRÖM, OF WIGGBYHOLM, SWEDEN.

SPRAYER PADDLE-WHEEL.

1,391,057.

Specification of Letters Patent. Patented Sept. 20, 1921.

Application filed March 10, 1920. Serial No. 364,708.

To all whom it may concern:

Be it known that I, AXEL HOLMSTRÖM, a subject of the King of Sweden, residing at Wiggbyholm, Sweden, have invented a certain new and useful Sprayer Paddle-Wheel, of which the following is a specification.

My invention relates to paddle wheels which are intended to carry paddles for stirring or spraying liquid.

10 The main purpose of my invention is to distribute the paddles disconnectedly and out of line so as to give nearly noiseless, mild and gentle contact and at the same time secure firm and powerful operation.

15 A further purpose is to divide the blow or impact of the blade or blades carried by the wheel so as to distribute the torque throughout the rotation of the wheel.

20 A further purpose is to cheapen the construction of the paddle wheel by making it of independent sections which may be fastened together in a predetermined order or in variant orders to make up the complete length.

25 Further purposes will appear in the specification and in the claims.

I have preferred to illustrate my invention by but one main form, among many which will occur to those skilled in the art 30 in view of this disclosure, selecting a form which is practical, efficient and inexpensive and which at the same time well illustrates the principles of my invention.

Figure 1 is a side elevation, partly in 35 section, of the preferred form of my invention.

Fig. 2 is a section upon line 2—2 of Fig. 1.

Fig. 3 is a perspective view of one of the end sections shown in Fig. 1.

40 Figs. 4 and 5 are perspective views of end sections similar to that in Fig. 3 but having modified edges.

Fig. 6 is a perspective view of an intermediate section showing other modifications.

45 In the drawings similar numerals indicate like parts.

Paddle wheels for stirring or distributing liquids are useful in many arts. Some used in etching are shown in my Patent No. 50 979,071 of December 20, 1910. Though I

find the greatest utility for the present paddle wheel in spraying liquids for etching purposes, and can use it in any of the relations for which spraying wheels are suited, I do not limit it to this use but may apply 55 it in other arts and for other than spraying purposes.

Where a single blade extends axially of the wheel for its full length, as in existing apparatus, and is dipped beneath the liquid 60 surface and removed from it at the rate of five hundred revolutions or more per minute,—not uncommon in etching—the torque from the impact is a maximum and action takes place simultaneously throughout the 65 length of the wheel, producing considerable noise and causing unbalanced strains upon the shaft. This is improved but little by using more than one blade about the circumference, as a high speed must still be 70 maintained to secure proper spraying.

Whether for spraying or stirring purposes I have overcome the objections to it by dividing the blade which dips into the liquid 75 into parts and staggering the parts as they are distributed lengthwise, to form the complete effective blade of angularly spaced sections so that one part of the length of the blade dips into the liquid at one time and another or other parts of the blade into the 80 liquid at other times until the entire length of the blade has been dipped. Then or in the mean time, the first blade or another blade in circular line with it may be dipped to begin a new series of operations. 85

Describing the drawing by way of illustration and not in limitation, in Figs. 1, 2 and 3 I show a sectional paddle wheel, whose blade is made up of parts 10, 11, 12, 13, 14, 15, 16 and 17. These extend from the wheel 90 in different angular positions and for convenience are here arranged in a helical form so that a line 18, drawn through the centers of the blade edges will form a helix. The several sections are mounted upon any suitable shaft 19, which is here shown as of non-circular cross section—square—but which may be of any section desired. Where it is of non-circular cross section it may be extended to form bearings, not shown, or the 100

bearings may be provided by hubs or other means mounted upon the shaft. Hubs capable of this purpose are shown upon the end sections at 20 and 21 and in this case are 5 the same size as the bodies 22 of the wheels. However, the usual purpose of these hubs is to afford a sealing surface with which an etching casing engages to prevent leakage of the etching liquid past the hubs.

10 The non-circular cross section of shaft has an advantage in the rigidity of the mounting of the several sections upon the shaft to prevent rotation; as they need only be slipped over the end and are at all times 15 thus rigidly held, but has a disadvantage in requiring that the relation between the blade upon a section and the section must be fixed preliminarily and can be changed only as the shaft permits the entire section to be 20 put on in different angular positions. In Figs. 2, 3 and 4 but four such shifts of position are permitted and two different forms of intermediate sections are required; while in Fig. 5 the octagonal opening permits the 25 staggering of the same blade section to any of the eight positions and requires different section form for some such purpose only as providing end hubs. In the case of a circular shaft section (such as in Fig. 6) the 30 most of the sections carrying the blades may also be alike. These like sections may then be staggered about the shaft in different angular positions to suit the need or preference, being held in place by suitable retaining 35 mechanism and corresponding in number and in angular displacement to the paddle wheel length which the width of the casing provides.

The sections shown in Fig. 1 upon the 40 square shaft may be held in place by a variety of means. The set screws 23 will ordinarily be sufficient. In addition to them, if desired, or instead of them the shaft 19 may be threaded at 19' to receive nuts 28 by 45 which all of the sections may be held tightly as a unit.

In Fig. 3 the blade is shown as having one straight face 24 which may be radial to the shaft axis, and a convex curved face 25, 50 meeting in a straight edge 26. The special advantage of the curved convex surface lies in the partial vacuum effect produced by it when it is the trailing surface, causing it to take up and carry more liquid than would 55 otherwise be the case.

Where the device is used for spraying liquids there is advantageous increase in the quantity of liquid sprayed in rotating the blade in a clockwise direction of Fig. 3 both 60 because of this vacuum effect and because the straight face 24 in that event picks up a larger quantity of the liquid than would be picked up by the curved face if it were the working face. Concaved faces 24' are 65 shown in Fig. 6 for the purpose of scooping

up additional liquid. The shapes of the faces may otherwise be varied to suit the needs or whim of the user, while obtaining part of the advantage of my invention.

The edge 26 need not be straight, as shown 70 but may have any suitable contour of which I have shown several different interrupted or serrated faces at 26' and 26" in Figs. 4 and 5.

In Fig. 5 I have shown openings 29 75 through which some of the liquid may be forced by movement of the blade and by the direction of whose walls the liquid may be directed away from the axis of the paddle for spraying purposes.

In the form in Fig. 6 I have shown multiple blades, here two, upon the same section and uniformly spaced.

Instead of the square opening 27 shown in Fig. 3, I show an octagonal opening 27' 85 in Fig. 5 and a circular opening 27" in the structure shown in Fig. 6, so that those sections may be turned to different angles to advantage. The sections may then be held against rotation by end clamping units 28 or 90 otherwise.

The material used for my wheel is not of the essence of my invention. Glass and porcelain are suitable.

I recognize that the disclosure of sectional 95 paddle wheels made by me herein will point out to those skilled in the art many other forms in which my invention may appear. I desire to cover by my claims all such as they come within the spirit and scope of 100 my invention.

Having thus described my invention, what I claim as new and desire to secure by Letters Patent is:—

1. A paddle wheel for spraying or surface 105 stirring of liquids, comprising a shaft, a plurality of sections upon the shaft, means for holding the sections against longitudinal and circumferential movement about the shaft, and separate blades upon the different 110 sections having recessed faces on one side of each blade, recessed through the blades and having convex trailing surfaces about the recess.

2. A paddle wheel for spraying or surface 115 stirring of liquids, comprising a shaft, a plurality of sections upon the shaft, means for holding the sections against longitudinal and circumferential movement about the shaft, and separate blades upon the different 120 sections having the trailing face thereof convex in curvature, and of substantially uniform width from the end to the hub.

3. A blade for a spraying paddle wheel having a radial leading face, an interrupted 125 edge and a convex trailing surface.

4. A blade for a spraying paddle wheel having a hub connection, a convex trailing surface and substantially uniform width 130 from the hub to the rim.

5. A blade for a paddle wheel having a hub connection, a convex trailing surface and an interrupted edge.

6. A blade for spraying paddle wheels which is solid from the hub to the rim and which has a convex trailing surface and an approximately radial leading surface.

7. A sectional spraying blade and hub construction in which the leading face of

one blade begins approximately in line with 10 the end of the trailing face of the next adjoining section.

8. A spraying blade and hub in which the trailing edge of the blade is convex and approximately merges into the surface of 15 the hub.

AXEL HOLMSTRÖM.
